VEHICLE DOOR LATCH

Waldemar A. Endter, Long Beach, Calif.

Application March 13, 1948, Serial No. 14,683

3 Claims. (Cl. 292—198)

1

This invention has to do with improvements in latching mechanisms adaptable particularly to vehicle doors. In certain of its aspects the invention contemplates improvements upon the type of mechanism disclosed in my copending application Serial Number 705,843 filed October 26, 1946, on Latching Mechanisms for Closures, with respect to the use of a door-carried keeper part releasable from a pillar-carried holding part or bolt, and to the adaptation for control of the keeper part and latched condition of the mechanism, of the type of control disclosed in a second copending application Serial Number 640,860 filed January 12, 1946, on Lock Control Mechanism.

Generally considered, the present latch assembly comprises a door-carried holding part functioning essentially as a keeper by virtue of its capacity for movement, relatively speaking, into and out of the path or location of a pillar-supported holding part or bolt. The assembly has take-up characteristics in that the bolt is spring urged against and in such relation to the keeper as to exert a constant closing or take-up thrust against the door in the latched condition of the parts. The latch parts are engaged by movement of the keeper into overlapping relation with the bolt as a result of swinging movement of the door as it approaches closed position, whereupon the bolt becomes responsive to exert a sustained thrust against the keeper. Release of the latch, from engaged condition is effected by manual controls, operable at the inside or outside of the door, to permit the keeper to move away from the bolt and out of overlapping relation, so that the door is free to open.

As indicated, my primary objects are directed to control of the keeper in a manner permitting its release by actuation of either the inside or outside operators, and, by the use of a second inside control or operator, e. g., push button type, maintaining the keeper against anti-latching displacement from the bolt when the parts are to assume a locked condition. Particularly contemplated is a control system whereby, in such locked condition, the normal releasing movement of the outside operator becomes ineffective to release the keeper, and the keeper is permitted to assume a locked condition from which it is not releasable, by closing the door while maintaining the outside operator in what otherwise would be a keeper releasing position.

In accordance with my preferred construction, I employ a keeper which is displaceable to accommodate the bolt in latched condition, and

2

then becomes blocked against release by a blocking element controllable by the outside and inside operators. Keeper releasing the outside operator is transmitted to the blocking element by a connection capable of an engaged condition in which such movement of the outside operator is transmitted, and a disengaged condition in which movement of the outside operator is ineffective to produce keeper releasing movement of the blocking element. Such conditioning of the connection is effected at the inside of the door, as by the aforementioned push button control, and in a manner causing the inside operator to become ineffective to release the blocking element, as by positively blocking releasing movement of the inside operator itself. By virtue of the disengaged condition of said connection and its association with the outside operator, the latter is made effective, in normally its keeper releasing position, to maintain the disengaged condition of the connection, and thus allow closing the door to in effect a locked condition of the keeper.

The invention has various additional features and objects, all of which together with the details of a typical and illustrative embodiment will be fully appreciated and understood from the following detailed description of the accompanying drawings, in which:

Fig. 1 is a general view taken in horizontal section through the mating edges of the door and pillar, showing the latch in engaged condition;

Fig. 2 is an enlarged view taken in the plane of line 2—2 of Fig. 4, showing the control parts at the inside of one flange of the door-contained angular housing;

Fig. 3 is a fragmentary elevation viewed from line 3—3 of Fig. 2, showing the engaged bolt and keeper assemblies;

Fig. 4 is a view taken on line 4—4 of Fig. 2;

Fig. 5 is a similar view showing the parts in changed positions;

Figs. 6, 7 and 8 are views taken in the plane of line 6—6 of Fig. 3, showing the bolt and keeper parts in progressively changed positions;

Figs. 9 and 10 are fragmentary sectional views taken respectively on line 9—9 and 10—10 of Fig. 6; and

Fig. 11 is an enlarged view illustrating certain parts of the bolt and keeper assemblies in engaged condition.

Referring first to Fig. 1, the latch mechanism, generally indicated at 15, is particularly adapted for application to an automobile door 16 which closes against the stationary pillar 17 and is

adapted to be crowded by the later described take-up action of the latch mechanism, against the usual pillar-carried cushion 18. The door is shown to carry an appropriate outside handle 19 within the forward tubular end 20 of which is contained push-button type outside operator 21, the functions of which will later appear.

As best indicated by Figs. 3, 6 and 11, the latch mechanism 15 may be regarded generally as comprising a door-carried keeper assembly 22, and a take-up type holding part or bolt assembly 23 stationarily supported by the pillar 17. Certain of the door mounted parts of the mechanism associated with the keeper and its control connections, are carried by an angular case 24 contained within the door 16 between its sheet metal sections 25 and 26, the flanges 27 and 28 carrying the hereinafter described parts of the keeper control mechanism.

Referring particularly to Figs. 6 to 8 and 11, the bolt assembly 23 comprises a housing 29 secured to the pillar 17 and having a bottom opening 30, the top surface of the housing being engageable against a door-carried roller 31 or other form of projection, so that in latched position, the bolt assembly has a dove-tail relation with the keeper, all as will later appear. The housing 29 contains a bolt 32 projecting downwardly through the opening 30, the bolt head having a curved keeper engaging face 33, and a safety catch recess 34. Within the housing the bolt has a circularly curved portion 35 engaging and retained within the correspondingly curved surface 36 of a cam 37, the latter having an outer curved surface 38, eccentric with relation to surface 36, and engaging a stationary curved abutment 39. Rotation of the cam in a counter-clockwise direction is limited by engagement of its straight surface 40 with the housing 29. The opposite end of the cam terminates at a shoulder 41 engageable against the bolt surface 42, as when the bolt and cam rotate together. The cam is constantly urged in a clockwise direction tending to thrust the bolt outwardly against the keeper, by a spring 43 carried by support 44, the free end 43a of the spring bearing against the laterally projecting end portion 45 of the cam. The bolt 32 is constantly urged in a clockwise direction by spring 46 carried by the support 44 and having its free end 46a bearing against lug 48 on member 49 formed integrally with the bolt or as a separate piece welded thereto.

Normally the springs 43 and 46 tend to maintain the bolt and cam in the positions illustrated in Fig. 6. Then as the bolt is displaced counter-clockwise to the position of Fig. 7 engagement of the bolt shoulder 42 with the end 41 of the cam causes the parts to rotate together. Thereafter, the bolt advances ahead of the cam as the bolt enters the keeper, say to the position of Fig. 11. The position of maximum projection taken by the bolt is represented by Figs. 6 and 8, in which the cam has rotated in a clockwise direction to the limit of its travel. Further details concerning this type of cam actuated floating bolt may be had by referring to my copending application Serial No. 783,184 on Floating Bolt Latch Mechanisms.

As most clearly illustrated in Figs. 9 to 11, the door-carried keeper assembly 22 comprises an open top housing 50 which supports the outer end of a shaft 51 extending through the end wall 52 of the door to terminate in a fixed supporting plate or deck 53. The keeper 54 comprises an elongated piece mounted for vertical

oscillation on the shaft 51, the keeper being displaceable downwardly within the housing 50 and having an upper surface 55 curved in conformity with the bolt curvature 33, the continuing keeper surface at 56 being substantially straight.

The keeper carries a pin 57 extending inwardly through registering openings 58 and 58a, see Fig. 10, respectively in the case flange 27 and door face 52 for connection with the control mechanism, as will later appear. Pin 57 carries a rotatable latch element 59 which is urged to rotate clockwise relative to the keeper 54, by a coiled spring 60 encircling the pin and bearing at one end against a projection 61 on the keeper, and at its opposite end against a lug 62 projecting inwardly from the element 59 within opening 58. A second lug 62a projecting from the opposite side of the element for engagement with the underside of the keeper, arrests rotation of the element under the influence of the spring, see Figs. 6, 7 and 11. At this point it may be mentioned that in Fig. 11, the keeper 54 has been illustrated in phantom by the dotted lines, to more clearly show the setting lever and latch element parts at the inside of the keeper.

Shaft 51 carries a rotatable setting lever 64 comprising an arm 65 about which is placed a correspondingly shaped sheath or shell 66, the opposite side of the lever being formed as a lug 67 for engagement with the latch element 59. The setting lever is constantly urged to rotate clockwise about the shaft 51, by a spring 68 encircling the shaft, one end of the spring bearing at 69 against the lug end of the lever, and the other end of the spring bearing against the housing 50 at 70.

A control arm or plate 71 is pivotally carried by shaft 51 at the inside of the case flange 27, see Fig. 9. As particularly shown in Fig. 10, pin 57 is carried by arm 71 so that the pin, keeper 54 and latch element 59 all are rotatable with arm 71 about the shaft 51. The arm is mounted for oscillation between one extreme position of engagement with a stationary stop 73, see Fig. 6, and the position of Fig. 8 in which the upper notched end 74 of the arm engages and is releasably held against return movement, by a blocking element 75 pivotally carried intermediate its ends by stationary pin 76.

Reference conveniently may be had now to the operation of the bolt and keeper assemblies as the door is swung from open to fully latched positions. With the door opened the parts assume positions illustrated in Fig. 6, which shows the keeper 54 to be held below or in offset relation to the bolt 32. As the door closes, the setting lever 64 engages the bolt housing 29, rotating the lever against the resistance of spring 68, and bringing the lever lug 67 against the end 78 of the latch element 59, thus causing the keeper 54 to be swung upwardly about shaft 51 for engagement with the bolt 32. Just in advance of the condition illustrated in Fig. 7, the keeper nose enters the bolt safety catch recess 34. Then as the door further closes, the bolt is displaced upwardly to override the top of the keeper and then swing downwardly to the latched position of Fig. 11. Here the bolt is urged by spring 46 in a direction of advancing or clockwise rotation, while spring 43 simultaneously urges the cam 37 to project the bolt outwardly against the keeper. The result is a take-up action tending to crowd the door against the cushion 18, progressively with the advancement of the bolt along

the keeper to the home position of Fig. 8. Upon advancement of the door or setting lever just beyond the position of Fig. 7, the blocking element 75 swings into the notched end 74 of arm 71 to hold the latter, together with the keeper, in the normal latched position of Fig. 8. Also as the door advances just beyond the position of Fig. 7, the setting lever lug 67 moves off the end face 78 of the latch element, with the result that the setting lever then is permitted to rotate independently, and relative to the keeper, as the lug 67 enters the notched end portion 79 of the latch element. Accordingly, in swinging from the position of Fig. 7 to that of Fig. 8, the setting lever 64 develops added tension in the spring 68, which becomes effective, upon release of the keeper, as will later appear, to enable the setting lever to thrust the door open by reason of the spring urged bearing of the arm against the stationary housing 29.

Referring now to Figs. 2 to 5, the blocking element 75 is urged to swing in the direction of arm 71, by coil spring 80 carried by pin 81 which serves also as a pivotal mounting for a bell crank arm 82. One end of spring 80 bears against the blocking element at 183, and the other end engages lug 184 to resist counterclockwise rotation of the arm 82. Normally, the latter is positioned by engagement with a stationary stop 181. Arm 82 is actuated by the outside operator 21, preferably of the push button type including a rod 186 having an inner head end 187 bearing against arm 82, inward movement of the rod being resisted by coil spring 188.

Downward swinging movement of the end portion 83 of arm 82 is transmittable to the blocking element 75 by way of a connection, generally indicated at 84 in Fig. 4, capable of an engaged position or condition in which movement of the outside operator is transmitted to the blocking element, and a disengaged condition in which movement of the operator is ineffective to actuate the blocking element. The connection 84 is shown to comprise an arm 85 which swings on a pin 86, clockwise rotation of the arm being resisted by spring 87 bearing against the arm-carried lug 88. The upper portion of the arm is established by engagement with the stationary stop 89. A bifurcated piece 90 is pivotally connected by pin 91 to the arm 85, and the assembly is swingable downwardly about pin 86 by engagement with the previously described arm end 83 with lug 92 on arm 85.

A member 93 rotatable about pin 94 has an arm portion 95, the end recess 96 in which receives one end 97 of a reciprocally movable link 98, the opposite turned end 99 of which is received, see Fig. 2, within the recessed or bifurcated end 103 of the blocking element 75. The in-struck case lug 73 confines link 98 for movement along the case flange 28. Member 93 is rotatable to move link 98 downwardly and release the element 75 from blocking relation with arm 71, by way of link 102 connected to the usual inside door handle, not shown, and having a pin and slot connection at 103 with the arm portion 104 of member 93. Clockwise rotation of member 93 from the position of Fig. 4, is resisted by the depending end 87a of coil spring 87, bearing against lug 105 carried by the curved arm extension 106 of member 93.

Assuming the parts to be positioned as in Figs. 2 and 4, inward movement of the outside operator rod 186 thrusts the bifurcated piece 90 downwardly against lug 107 on arm 95, causing the

latter to pull the link 98 down and swing the blocking element 75 to position releasing arm 71. The resultant rotation of member 93 occurs independently of the inside operator actuated link 102 by virtue of the pin and slot connection at 103.

A rotatable control lever 110 carried by pin 94 is pivotally connected at 111 with the usual inside push button rod 112, and is rotatable between the positions of Figs. 4 and 5 by vertical displacement of the push button rod. One primary function of the control lever 110 is to permit selective conditioning of the connection 84 between its engaged and disengaged positions, and therefore to selectively render the keeper releasable, or non-releasable, in response to actuation of the outside operator. Portion 113 of the control arm carries a lateral projection or lug 114 received within the end recess 115 of the bifurcated piece 90 so that oscillations of arm 110 reciprocally swing member 90 between the illustrated positions of Figs. 4 and 5.

As the push button rod 112 is thrust down to the position of Fig. 5, the resulting rotation of arm 110 swings piece 90 to a position offset with relation to lug 107, such that vertical reciprocations of the piece by the outside operator are ineffective to transmit motion to the keeper release. Thus this condition may exist when it is desired to lock the door from the inside, and against release from the outside, by thrusting down the push button rod 112. The same push button manipulation may be used to lock the door against release by the inside operator, as by bringing lug 201 in the path of hook 200 on link 102. Member 90 however is restorable to its operative position of Fig. 4, either by elevating the push button rod, or by closing the door with the outside operator in a normal position, permitting the setting lever 64 to swing arm 71 under lever 75, with resultant simultaneous swinging of the latch with member 95, causing its extension 106 to engage lug 118 of element 90 and throw it to operative position. Positive establishment of arm 110 in the two limiting positions shown, is facilitated by an over-center spring 119 connected to the arm 120 and acting to urge member 110 fully to either of its limiting positions, as the case may be.

The control lever 110 is further controllable by an appropriate key actuated mechanism, generally indicated at 121, which may comprise a key controlled rotor 122 having shoulders 123 and 124 engageable with the end of arm 120 to throw the lever 110 from either to the other of the illustrated positions. Thus the door may be key locked from the outside to place the parts in the position of Fig. 5 in which, as explained, the outside operator is ineffective to release the keeper.

Now assume the door to be open and that it is desired to fully close the door bringing the latch parts into locked condition, at least with respect to their release by the outside operator. By thrusting down the push button rod 112, and holding the outside operator 21 at its in position against resistance of spring 188 so that the lug 118 of element 90 is moved out of the path of travel of the extension 106 of member 95, the bolt and keeper parts will fully engage in latched condition while the control parts remain in the condition of Fig. 5. Thereafter, unless the control lever 110 is thrown by manipulation of the push button rod 112 or the turning of rotor 122 by key operation from the outside of the door, to

restore the parts to the positions of Fig. 4, the connection 84 will remain in its disengaged condition of Fig. 5 in which, as previously indicated, reciprocations of the outside operator rod 183 are ineffective to disturb the blocked and latched condition of the keeper. Connection 84 remains in a disengaged condition because, when in the Fig. 5 position, vertical reciprocation of the part 88 may occur without engaging lug 187.

I claim:

1. In a latching mechanism having a case structure provided with a face applicable to the edge of a door that is adapted to be swung closed into opposing relation with the edge of a stationary pillar, the combination comprising: an elongated keeper mounted adjacent one end thereof on the outside of said case structure for pivotal movement between latching and releasing positions about an axis substantially normal to said face, said keeper having an edge surface adapted in the latching position of said keeper to be disposed in overlapping engagement with a bolt structure mounted on the edge of the pillar; movable blocking means for automatically maintaining said keeper in latching position; a lever mounted for pivotal movement about the same axis as said keeper and engageable by the bolt structure for movement thereby; a catch movably mounted on said keeper and engageable by said lever for moving said keeper to latching position; and means engageable by said catch for releasing its lever-engagement when said keeper reaches latching position.

2. The structure defined in claim 1 including a spring urging the lever for movement against the bolt structure.

3. In a latching mechanism having a case structure provided with a face applicable to the edge of a door that is adapted to be swung closed into opposing relation with the edge of a stationary pillar, the combination comprising: an elongated keeper mounted adjacent one end thereof on the outside of said case structure for pivotal movement between latching and releas-

ing positions about an axis substantially normal to said face, said keeper having an edge surface disposed substantially normal to said face, said surface being concavely-curved and adapted in the latching position of said keeper to be disposed in overlapping relation with a bolt structure mounted on the edge of the pillar; an arm mounted for pivotal movement about the same axis as said keeper and secured thereto at a location adjacent the other end thereof; a movable blocking member automatically engageable with said arm to maintain said keeper in latching position; a lever mounted for pivotal movement about the same axis as said keeper and engageable with the bolt structure for movement thereby; a catch pivotally mounted on said keeper and engageable by said lever for moving said keeper from releasing to latching position by movement of said lever, and fixed abutment means engageable by said catch for moving the same out of engagement with said lever when said keeper is in latching position.

WALDEMAR A. ENDTER.
